(57) CLAIM

The ornamental design for a stool, as shown and described.

DESCRIPTION

FIG. 1 depicts a perspective view of the stool of the invention.
FIG. 2 depicts a front view of the stool of the invention.

FIG. 3 depicts a perspective left side view of the stool of the invention.

FIG. 4 depicts a perspective right side view of the stool of the invention.

FIG. 5 depicts a top view of the stool of the invention; and,
FIG. 6 depicts a bottom view of the stool of the invention.
The accompanying drawings, which are incorporated into and form a part of the specification, illustrate the present invention.

The broken lines depicted in the drawings depict environmental features that form no part of the claimed design.

1 Claim, 6 Drawing Sheets
